Application June 15, 1942, Serial No. 447,055

10 Claims. (Cl. 158—28)

This invention relates generally to pumping devices and in particular to a pump of diaphragm type.

Pumps of diaphragm type are well known in the prior art. These pumps generally have the diaphragm thereof operated by mechanical means. Where a pump of this type is utilized in conjunction with the fuel supply of an internal combustion engine and is mechanically connected therewith the diaphragm is operated to pump fuel concurrently with the rotation of the engine. Thus when the engine is being shut down, fuel will continue to be pumped until the engine has come to a standstill. In installations where the engine is used as a direct power supply for associated apparatus, such as for operating heating apparatus having a burner supplied with fuel by the engine diaphragm pump this continued pumping action, while the engine is being stopped, is objectionable because of the tendency to flood the burner.

In the usual assembly of a diaphragm pump in the fuel system of an associated engine, such as an automobile engine, the pump is operated at cam shaft speed. However, on small utility engines, such as fractional horsepower air-cooled type engines, and the like, a cam shaft is not used so that the diaphragm pump is operated at crank shaft speed. By virtue of the high rotational speed of the crank shaft the follower portion of the pump generally associated with the pump diaphragm and operatively connected with a cam on the crank shaft tends to wear the cam excessively within but a very short period of operation. In these utility engines provision of a gear reduction means between the pump and the crank shaft appreciably increases the initial cost as well as the bulk of the pump-to-engine connecting mechanism so as to practically negate the use of reduction means on engines of this type. As a result most utility engines utilize gravity feed fuel systems. Thus on a shutting down of the engine, either intentionally or accidentally, fuel continues to flow through the fuel system.

As a result with a fuel system having a mechanically operated pump or in a system of gravity feed type fuel is accumulated in the combustion portion during engine shut down which interferes with the starting operation of the burner. Further this accumulated fuel at times might cause explosions of a serious nature in the burner when burning is initiated therein.

It is an object of this invention therefore to provide improved pumping apparatus.

Another object of this invention is to provide

an improved pump of diaphragm type which is operable in response to variations in fluid pressures applied on the diaphragm means thereof.

A further object of this invention is to provide a diaphragm pump capable of being operated in response to the variable fluid pressures effected by the cylinder of a combustion engine during normal engine operation.

Another object of this invention is to provide a diaphragm pump which is of a rugged and simple construction, light in weight, efficient in operation, and directly responsive in operation to alternately high and low fluid pressures applied on the diaphragm means thereof.

A feature of this invention is found in the provision of a diaphragm pump in the fuel supply of an internal combustion engine, which is responsive in operation to the exhaust impulses discharged from such engine.

Yet another feature of this invention is found in the provision of a diaphragm pump for supplying fuel to the burner of heating apparatus operated solely by an associated internal combustion engine, in which the pump diaphragm means is arranged to be acted upon by the fluid passing through the engine cylinder so as to be responsive in operation to the variations in the pressures of such fluid to control the fuel feed to the burner.

Further objects, features and advantages of this invention will become apparent from the following description when taken in connection with the accompanying drawings in which:

Fig. 1 illustrates the improved diaphragm pump of this invention utilized in the fuel supply of a burner for air heating apparatus operated in conjunction with an internal combustion engine;

Fig. 2 is a longitudinal sectional view of the pumping means illustrated in Fig. 1 showing its adaptation for operation in response to the exhaust impulses from an internal combustion engine;

Fig. 3 is a sectional fragmentary view showing a modified means for fluid connecting the pump of Fig. 2 with the exhaust conduit for the engine;

Fig. 4 is illustrated similarly to Fig. 2 and shows the adaptation of the pump for operation in response to the fluid pressures in the intake line of an internal combustion engine; and

Fig. 5 is a longitudinal sectional view of a modified form of the invention adapted to be operated either at the intake or the exhaust of an internal combustion engine.

In the practice of this invention there is provided a diaphragm pump having a casing with

diaphragm means extended thereacross to form expansible pumping and pressure chambers therein, with the diaphragm means constituting a flexible wall portion for each of such chambers. The pumping chamber has an inlet and an outlet each of which has a valve unit therein responsive in operation to the liquid pressures occurring in the pumping and pressure chambers to control the liquid flow through the pump. The pumping action is effected in the usual manner by movement of the diaphragm means to expand and contract the pumping chamber. This movement of the diaphragm means is accomplished by the fluid connection of the pressure chamber with the exhaust conduit or intake line of an internal combustion engine. The pump may be included as a part of the engine fuel system or operated by the engine to supply liquid to apparatus associated therewith. The movement of the diaphragm means in response to the exhaust impulses in the engine exhaust conduit, provides for the operation of the pump only when the engine is in actual operation. In other words when the engine is shut down the movement of the diaphragm means and in turn the moving of fuel by the pump is discontinued regardless of whether or not the engine continues to rotate. The pump thus functions to discharge fuel only when actual firing takes place in the engine.

With reference to the drawings the pump 10 of this invention is illustrated in Fig. 1 as being included in and common to the fuel supply systems of an internal combustion engine 11 and a burner or combustion chamber 12 of an air heating apparatus operated by the engine. The engine 11 includes an air cooled cylinder 13, an exhaust conduit 14 for the cylinder 13, and a shaft 16 for carrying a fan 17 which supplies combustion air and air to be heated to the heater apparatus. The engine 11, the scroll or housing 18 for the fan 17, and a fuel tank 15 for the engine 11 and combustion chamber 12 are supported on top of the combustion chamber and in alignment longitudinally thereof.

The combustion chamber 12, which is shown in development in Fig. 1 for the purpose of clarity, is of a substantially cylindrical shape and divided into four axially extended but connected passages 19a-19d by partition means 21. The combustion chamber 12 is closed at one end by a cover plate 22 and at its opposite end by the bottom portion 23 of a substantially cup-shaped member 24. Heat radiating fins 26 are angularly spaced about and extended longitudinally of the combustion chamber 12 to retain the same in a spaced relation relative to the heater housing or casing 27 and provide an annular air passage 28 about the combustion chamber for air to be heated. The passage 28 is co-extensive in length with the combustion chamber 12 and the member 24 and is separated from an air supply chamber 29 by a partition member 31 positioned about the member 24 and arranged transversely of the heater housing 27. The air supply chamber 29 is seen from Fig. 1 to be in longitudinal alignment with the combustion chamber 12 and defined by the member 24, partition plate 31 and the end 32 of the heater housing 27.

Air to be heated enters an inlet 33 in the fan housing 18 and is discharged into the passage 28 for circulation about the combustion chamber 12 and outwardly from the heater through an outlet 34. The air for combustion delivered to the air supply chamber 29 is also provided by the fan 17

through an inlet opening 36 formed in the peripheral rim of the cup-shaped member 24. In other words the air from the fan 17 enters the passage 28, with a portion of such air being by-passed through the inlet 36 into the air supply chamber 29, and the remaining portion thereof being circulated through the passage 28 and about the combustion chamber 12.

The air for combustion is mixed with the fuel supplied by the pump 10 in a fuel conditioning means, indicated generally as 37, which includes a tubular casing 38 having a substantially closed end portion 39 extending into the air supply chamber 29, and an opposite end 41 which is open and in fluid communication with the combustion passage 19a of the combustion chamber 12. An air and fuel mixing chamber 42 is located at the closed end of the casing 38 and is separated from an equalizing chamber 43 by a plate member 44 having perforations 46 therein. The equalizing chamber 43 in turn is both defined and separated from the combustion chamber passage 19a by a perforated heat insulating plate 47. Extended substantially axially through the casing 38 is the end portion 48 of the engine exhaust conduit 14. The casing 38 and partition plate 44 are provided in a heat conducting material and are in thermal connection with the conduit end portion 48 so as to readily receive heat from the exhaust gases passing therethrough. The heat thus radiated from the exhaust conduit portion 48 is adapted to heat the air and fuel mixing means 37 to at least a fuel vaporizing temperature to facilitate the mixing together of the fuel and air admitted therein, with such vaporous mixture being ignited by an igniter element 49 located in the passage 19a adjacent the end 41 of the casing 38. The igniter 49 is connected in the ignition circuit for the engine, which includes a spark plug 50 and a magneto (not shown).

A fuel nozzle or delivery means 51 carried at the casing end 39 and located within the air supply chamber 29 is connected with the outlet 52 of the pump 10 through a pipe 53. A portion of the air for mixing with the fuel enters the nozzle 51 through ports 54 and travels with this fuel into the mixing chamber 42. Further air is admitted directly into the mixing chamber 42 through apertures 55 in the casing 38 arranged about the fuel nozzle 51. The fuel thus entering the mixing chamber 42 is heated to at least a fuel vaporizing temperature by the heat from the exhaust conduit end portion 48 for intimate mixing with the air in such chamber. This vaporous mixture passes into the equalizing chamber 43 through the apertures 46 in the partition plate 44. The equalizing chamber acts to reduce the turbulence in the mixture, as effected by the air flow in the chamber 42, and to disperse the mixture substantially uniformly across the entire cross section of the casing 38 so that a mixture of substantially uniform fuel characteristics passes through the perforated heat insulating plate 47 and into the combustion passage 19a where it is ignited by the spark means 49 and mixed with the engine exhaust gases from the conduit 14 for burning therewith. The admission of the air and fuel to the fuel conditioning means 37 thus controls directly the operation of the combustion chamber 12. The exhaust gas from the combustion chamber 12 is discharged therefrom through an exhaust assembly 60 in fluid communication with the combustion passage 19d and extended through the housing end 32.

In the operation of the heater it is desirable that the operation of the pump follow closely the operation of the engine. Thus as was previously mentioned in connection with the prior art, the usual type diaphragm pump which is mechanically connected with an engine such as 11 continues to pump fuel so long as the engine rotates. It is apparent, therefore, that when the engine 11 is shut down fuel will be supplied to the conditioning means 37 during the time interval between the shutting down of the engine and its coming to an actual stop. This fuel accumulates in the conditioning means or in the combustion chamber 12 so as to flood the same. As a result an excess of fuel is present in either the conditioning means 37 or the combustion chamber 12 so as to interfere with the proper starting of the heater. Further the vapors resulting from the accumulated fuel might result in a combustible mixture being present in the combustion chamber 12, prior to a flow of air therethrough sufficient to move the vapors through the combustion chamber, which effects an initial explosion of objectionable proportions. These difficulties are entirely eliminated by the diaphragm pump of this invention one form of which is shown in Fig. 2.

With reference to Fig. 2 the pump 10 is seen to include a housing comprised of casing portions 56 and 57 having flange portions 58 and 59, respectively, adapted for mating engagement and secured together by screws or the like 61. A pumping chamber 62 and a pressure chamber 63 are formed within the pump housing by a diaphragm 64 extended transversely of the pump housing with the marginal edge thereof retained between the flange portions 58 and 59. The diaphragm 64 is composed of a usual resilient material to provide for its deflection in an up and down direction as viewed in Fig. 2. It is seen, therefore, that the diaphragm 64 forms a common flexible wall for the chambers 62 and 63 to provide for the expansion and contraction of such chambers. The pumping chamber 62 has an inlet 66 and an outlet 52 each of which is provided with a valve unit 67 and 65, respectively, including a disc 68 normally retained on a corresponding seat portion 69 by a spring 71, the discs 68 being opened in response to the liquid pressures acting thereon to permit a flow of liquid in one direction. On an increase in pressure in the pressure chamber 63 the diaphragm 64 is moved or deflected upwardly as viewed in Fig. 2 whereby to contract the pumping chamber 62 and increase the pressure on the liquid therein. This increase in pressure lifts the disc 68 in the valve unit 65 to permit fuel being discharged through the outlet 52. On a release or decrease of the pressure in the chamber 63 the diaphragm 64 is moved downwardly as viewed in Fig. 2 by the action of a spring 72 arranged in compression within the liquid or pumping chamber 62. This action of the spring 72 expands the chamber 62 to decrease the pressure therein, whereby the disc 68 in the valve unit 67 is lifted away from its corresponding seat against the pressure of a corresponding spring 71 to permit the drawing or passage of fuel into the pumping chamber 62 through the inlet 66, which is connected by pipe 70 to the fuel tank 15. On an increase of pressure in the pressure chamber 63 this fuel is discharged through the outlet 52 as above explained.

The increase and decrease of pressure in the pressure chamber 63 is accomplished in the pres-

ent invention by fluid connecting the pressure chamber 63 with the exhaust conduit 14 of the engine 11. In the operation of an internal combustion engine it is well known that the exhaust impulses or discharges therefrom are emitted in succession so as to create or effect a pressure wave in the engine exhaust conduit. In other words each exhaust impulse may be considered as having a mass, which passes through the exhaust conduit at a certain velocity. As this mass progresses through the exhaust conduit it produces a pressure at any point therein, which pressure is immediately reduced on passage of the mass beyond such point. The pressure in the exhaust conduit is thus of a wave form having alternate high and low points thereon. Referring, therefore, to Fig. 2 the flow of the exhaust gases through the exhaust conduit 14 at the connection 75, between the pressure chamber 63 and exhaust conduit 14, effects alternate high and low pressures at the connection 75 and in turn in the pressure chamber 63. Thus when an exhaust impulse or mass of exhaust gases is passing through the exhaust conduit the pressure in the pressure chamber 63 is alternately increased and decreased. When the pressure in the chamber 63 is increased the diaphragm 64 is moved upwardly, as viewed in Fig. 2, against the pressure of the spring 72. This movement of the diaphragm constitutes the working stroke for the pump and serves to discharge fuel through the outlet 52. On passage of the exhaust impulse beyond the connection 75 the pressure in the chamber 63 is decreased so as to permit the movement of the diaphragm 64 downwardly, as also viewed in Fig. 2, in response to the action of the spring 72. This movement of the diaphragm 64 provides the suction stroke for the pump 10. In some instances the spring 72 may be eliminated by virtue of the fact that the pressure decrease following the passage of the mass of exhaust gases beyond the connection 75 is sufficient to pull the diaphragm 64 downwardly.

It is unnecessary that the diaphragm 64 be of any particular heat resistant material since the exhaust gases in the pressure chamber 63 are not continuously admitted thereto and withdrawn therefrom. In other words the initial exhaust gas admitted into the pressure chamber 63 is substantially retained therein during subsequent operation of the pump 10, and acts as a column or quantity of gas which is acted upon by the exhaust gases normally passing through the exhaust conduit 14. Since this quantity of initial gas becomes cooled by its retention in the chamber 63 and connection 75 it acts as a heat insulator relative to the diaphragm 64 and protects the same from the heat of the exhaust gases normally passing through the exhaust conduit 14. It is seen, therefore, that each exhaust discharge or impulse effects a working stroke of the pump, with the interval or space between successive exhaust impulses providing an interval of low pressure in the chamber 63 and correspondingly in the pumping chamber 62 to provide a suction action for the pump 10.

As shown in Fig. 2 the extension of the connection 75 within the exhaust conduit 14 is generally not critical, so that the connection can terminate substantially within the periphery of the conduit 14 or may extend therein. However, where the pressure as effected by an exhaust discharge is relatively low the connection 75 may be formed, as indicated in Fig. 3 for the connec-

tion 75', with an elbow portion 73 having its open end flared and faced in the direction of the exhaust flow. The full pressure of the exhaust discharge, therefore, acts directly against the column of exhaust gases in the connection 75' to utilize such pressure to the fullest extent. It is apparent, of course, that the increase in pressure in the exhaust conduit resulting from the passage of the exhaust impulses therethrough is effected as a result of a back pressure in the exhaust conduit. It is desirable, therefore, that the connection 75 or 75' for the pump 10 be located on a portion of the exhaust conduit 14 capable of having a back pressure produced therein.

As above described it is seen that a working stroke of the diaphragm 64 is accomplished in response to the action thereon resulting from an exhaust impulse or discharge passing through the exhaust conduit 14. The pump 10 therefore, is operative only when exhaust gases are passing through the conduit 14 and is rendered inoperative on stopping or cessation of such exhaust flow. Thus on shutting down of the motor 11, and specifically the cutting off of the ignition thereof, active combustion therein is stopped so that only residual exhaust gases are emitted from the exhaust conduit 14. These residual gases tend to flow through the exhaust conduit 14 at a substantially constant pressure which is far below the pressure created therein by the high velocity flow of exhaust gases during normal engine operation. On shutting off the engine ignition, therefore, the pump 10 is rendered inoperative so that fuel to the fuel conditioning means 37 is stopped substantially concurrently with the cutting off of the engine ignition. Since air from the fan 17 continues to be supplied into the conditioning means 37 from the air supply chamber 29 any lagging rotation of the engine 11, after shut down functions to scavenge the conditioning means 37 and combustion chamber 12 of any residual fuel. Thus on later starting of the heater apparatus the combustion chamber 12 is free of any accumulated or residual fuel vapors so that combustion is initiated efficiently and smoothly and without danger of explosion.

Since the pump 10 is responsive in operation to the occurrence of an actual firing of the engine 11 it is rendered inoperative during any protracted or prolonged period of misfiring by the engine. In other words when the engine fails to operate normally and misses fire frequently before coming to an accidental shutdown, the pump 10 will operate to automatically stop the supply of fuel through the fuel system during the period of misfiring. The fuel supply is thus closed by the time the engine comes to a standstill.

Although the pump of Fig. 2 has been described above relative to its operation with the exhaust conduit 14, it may also be operated at the intake to the engine cylinder 13. When the pump is to be operated at the engine intake the spring 72 is arranged within the pressure chamber 63, as is illustrated in Fig. 4. On the suction stroke of the engine piston a suction pressure is effected in the intake line 74 and pressure chamber 63 which acts to draw the diaphragm 64 downwardly, as viewed in Fig. 4 against the pressure of the spring 72. During the remaining portion of the engine cycle the pressure in the intake passage 74 and in the chamber 63 is increased to permit the spring 72 moving the diaphragm 64 in a reversed direction. The action of the spring 72 thus actuates the diaphragm 64 to effect a

working stroke thereof, with the suction stroke of the diaphragm being accomplished by the suction intake pressure in the engine intake 74.

A modified form of the invention is illustrated in Fig. 5 in conjunction with an internal combustion engine 11a having at least two cylinders 13a and 13b, with corresponding exhaust conduits 76 and 77 extending from the exhaust openings 76a and 77a thereof. The pump 10' has a housing comprised of four casing sections including two corresponding end sections 78 and 78' and corresponding intermediate sections 79 and 79'. A working or pumping diaphragm 81 is extended across the pump housing with the marginal edges thereof retained between the end casing 78 and the intermediate casing 79, while an actuating diaphragm 82 is positioned across the pump housing with the marginal edges thereof held between the end section 78' and the intermediate section 79'. A third or idling diaphragm 83 has the marginal edges thereof secured between the inner sections 79 and 79', all three of the diaphragms 81, 82 and 83 being connected for movement together by a connecting pin or rod 84. The diaphragm 81 forms a flexible wall for a pumping chamber 62' located within the end section 78. Two pressure chambers are utilized in this embodiment of the invention, one pressure chamber 86 being formed between the diaphragms 82 and 83 in the intermediate section 79' and the second pressure chamber 87 being formed by the diaphragm 82 within the end housing section 78'. The chamber 85 formed between the diaphragms 81 and 83 provides no function in the operation 35 of the pump and is formed with a bleeder opening 80 to prevent any build up of pressure therein. The pressure chamber 86 is fluid connected through a connection 88 with the exhaust conduit 76, and the pressure chamber 87 is in communication with the exhaust conduit 77 through a tube 89. The passage of an exhaust impulse from a corresponding cylinder associated with the exhaust pipes 76 and 77 produces a pressure wave therein as was fully explained above in connection with Fig. 2.

With the engine cylinders 13a and 13b adapted to be fired in succession the pressure in the chambers 86 and 87 varies alternately. In other words when the pressure in the chamber 86 is at a maximum value the pressure in the chamber 87 is at a minimum value and conversely a high pressure in the chamber 87 occurs when a low pressure exists in the chamber 86. The alternate occurrence of these high pressures on opposite sides 55 of the diaphragm 82 acts to move the same in opposite directions to in turn actuate the working diaphragm 81, the reversed movement of the diaphragm 81 providing for a movement of the fuel by the pump 10' in a manner which is similar in all respects to that described for the diaphragm 84 in Fig. 2. By virtue of the connecting member 84 being common to all three of the diaphragms 81, 82 and 83 it is readily apparent that any increase in pressure in the chamber 86 acts against both of the diaphragms 82 and 83 tending to move the same in opposite directions. However, by virtue of the large area of the diaphragm 82 relative to the diaphragm 83 the diaphragm 83 is moved in the direction of movement of the diaphragm 82.

In the operation of the pump 10' from the engine intake rather than from the engine exhaust the structure thereof remains unchanged and intake lines are substituted for the exhaust lines 76 and 77. Since the pump 10' is operated en-

tirely by high and low pressures acting alternately on opposite sides of the diaphragm 82 these pressures will occur in the chambers 86 and 87 as a result of the variations in the engine intake lines so that the pump 10 will operate in all respects as above described for exhaust operation.

As shown in Fig. 1 the pump 10 is illustrated as being common to the fuel supply systems for both the engine 11 and combustion portion 12, the engine fuel system including a supply line 95 connected to the pump feed line 53, and having therein a sediment bowl 91 and a carburetor 92. Since the pump 10 is inoperative until firing actually occurs in the engine 11 it is apparent that no fuel is supplied to the feed line 53 until after the engine is in operation. This operation of the pump, however, does not interfere with the starting of the engine because of the reserve fuel initially present in the sediment bowl 91 and carburetor 92. It is apparent, therefore, that the pump of this invention is entirely adapted to operate satisfactorily in the fuel system of an internal combustion engine. In one embodiment of the invention operated in conjunction with a single cylinder four cycle engine rated at $\frac{1}{8}$ horse power, a capacity of five gallons per hour was accomplished when using a three sixteenth inch tube at the outlet 52. In this embodiment of the invention the working diaphragm had a maximum amplitude of three sixteenths inch. With the tube or line 53 at the outlet 52 of a somewhat restricted construction, for example having an inner diameter of .050 inch, a constant pressure of one pound per square inch was maintained in the line 53 with a delivery or capacity of one and one-half gallons per hour. It is seen, therefore, that the discharge of the pump is sufficiently ample for normal engine operation and capable of operating against appreciable line pressures.

From a consideration of the above description and drawings, therefore, it is seen that the invention provides an improved diaphragm pump which is capable of being operated entirely in response to alternate high and low pressures acting on the diaphragm means therefor. As a result the bulk and weight of the pump is appreciably reduced, and when used in connection with an internal combustion engine all of the actuating mechanism usually required for driving or operating the pump is entirely eliminated. The pump is simple in design and rugged in construction and capable of producing relatively high operating pressures. It is obvious of course that the pump is not restricted in operation to the intake and exhaust of an internal combustion engine, but can be operated by any means capable of producing alternate high and low fluid pressures.

Although the invention has been described specifically with reference to several preferred embodiments thereof it is to be understood that it is not so limited since modifications and alterations can be made therein which are within the full intended scope of this invention as defined by the appended claims.

I claim:

1. In combination with an internal combustion engine having a pair of alternately operated cylinders and a fluid passage individual to and in fluid connection with each cylinder, with the fluid in said passages creating alternate high and low pressures therein, a liquid pump including a casing having a plurality of diaphragm means therein, means common to said diaphragm

means connecting the same for movement together, said casing having a pumping portion therein with one of said diaphragm means constituting a flexible wall for said pumping portion, and a fluid portion with another of said diaphragm means extended thereacross, and means connecting said cylinder fluid passages with said fluid portion at different sides of said last-named diaphragm means.

2. In combination with an internal combustion engine having two alternately operated cylinders each provided with a corresponding opening for carrying exhaust gases therefrom, a liquid pump including a casing, a pair of diaphragm means in said casing separated from each other but connected for movement together, means connecting said exhaust openings respectively to different sides of one of said diaphragm means, whereby the exhaust discharges through said exhaust openings act on said one diaphragm means to reversely move the same, and a pumping chamber in said casing having a wall portion formed by the other of said diaphragm means to expand and contract the same.

3. In combination with an internal combustion engine which includes at least one cylinder and is provided with an exhaust opening, heating apparatus including means defining a combustion chamber, air moving means driven by said engine to supply air to said combustion chamber, a fuel pump actuated by the exhaust gases transmitted through said exhaust opening from said cylinder during operation of said engine, and means including said fuel pump for delivering fuel to said combustion chamber only when fuel combustion occurs in said engine.

4. In combination with an internal combustion engine which includes a cylinder and an exhaust conduit, heating apparatus including means defining a combustion chamber, air moving means driven by said engine to deliver combustion air to said combustion chamber, a fuel pump actuated directly in response to pressure fluctuations which are produced in the exhaust gases traversing said conduit by the intermittent combustion of fuel within said cylinder, and means including said fuel pump for delivering fuel to said combustion chamber only when fuel combustion occurs in said engine.

5. In combination with an internal combustion engine which includes at least one cylinder and is provided with an exhaust opening, heating apparatus including means defining a combustion chamber, air moving means driven by said engine to supply air to said combustion chamber, a fuel pump actuated by the exhaust gases transmitted through said exhaust opening from said cylinder during operation of said engine, means including said fuel pump for delivering fuel to said combustion chamber only when fuel combustion occurs in said engine, and means for utilizing the heat energy of said exhaust gases to preheat the fuel before it is delivered to said combustion chamber.

6. In combination with an internal combustion engine which includes at least one cylinder and is provided with an exhaust opening, heating apparatus including means defining a combustion chamber, air moving means driven by said engine to supply air to said combustion chamber, a fuel pump actuated by the exhaust gases transmitted through said exhaust opening from said cylinder during operation of said engine, means including said fuel pump for delivering fuel to said combustion chamber only when

fuel combustion occurs in said engine, and means including said pump for also delivering fuel to said engine.

7. In combination with an internal combustion engine which includes moving parts, heating apparatus including means defining a combustion chamber, air moving means driven by said engine to deliver combustion air to said combustion chamber, a fuel control device actuated by said engine only when fuel combustion is occurring in said engine and regardless of whether said moving parts are at rest or are moving, and means including said device for delivering fuel to said combustion chamber only when said device is operating.

8. In combination with internal combustion heating apparatus including means defining a combustion chamber, means for producing a heated fluid and for discharging said fluid with fluctuations in the discharge pressure thereof, a source of fuel for said heating apparatus, means actuated by the pressure fluctuations in the fluid discharged by said second-named means for pumping fuel from said source to said combustion chamber, and means for utilizing the heat energy of said discharged fluid to preheat the fuel before admission to said combustion chamber.

9. In combination with internal combustion heating apparatus including means defining a combustion chamber, means for producing heated gases and for discharging said gases with fluctuations in the discharge pressure thereof, a source

5 of fuel for said heating apparatus, means fluid connected with said second-named means and actuated by the pressure fluctuations in the gases discharged by said second-named means for pumping fuel from said source to said combustion chamber, and means for transferring heat energy from said gases to the fuel prior to admission of the fuel into said combustion chamber and for then discharging the heated gases into said

10 combustion chamber.

15 10. In combination with means defining two fluid passages adapted to have alternate high and low fluid pressures developed therein at related intervals such that each period of high pressure in either passage corresponds to a period of low pressure in the other passage, a fluid pump including a casing, three diaphragms in said casing, means connecting said diaphragms together for concurrent movement, the first of said diaphragms defining a pumping chamber within said casing, the second and third diaphragms dividing a portion of the space within said casing into two actuating chambers which are respectively disposed on opposite sides of said third diaphragm, and the first and second diaphragms defining a fourth chamber within said casing, said casing being provided with a breather passage communicating with said fourth chamber, and means respectively and individually connecting said fluid passages with said actuating chambers.

20 25 30 HARRY B. HOLTHOUSE.
